UPWARD ACTING DOOR AND REMOVABLE MULLION THEREFOR

Joseph E. Casse, Detroit, Mich., assignor to Crawford Door Company, Detroit, Mich., a corporation of Michigan

Application January 13, 1939, Serial No. 250,688

13 Claims. (Cl. 20—20)

This invention relates to a removable mullion or stile between adjoining closures for an opening such as a doorway and includes an upward acting door construction having adjoining doors in the doorway guided by a vertical mullion or stile which is adapted to be removed from the doorway when the doors are in open position to provide an unobstructed opening.

It is frequently desirable to close wide doorways with independent upward acting adjoining closures to avoid use of very large and heavy doors and to make possible an opening of only part of the doorway. This requires doors or closures which extend only partly across the width of the doorway. Such doors or closures must be guided or supported along their adjoining edge portions by means of a stationary vertical mullion, post or stile. These supports or guides, however, are objectionable since they obstruct the doorway when two adjoining closures are open and prevent passage of wide bodies through the doorway.

This invention now provides the required guide or support, hereinafter referred to as a mullion, in a removable form so that the same can be taken out of the doorway when adjoining closures are in open position.

While the invention will hereinafter be specifically described in connection with a pair of adjoining upward acting garage doors, it should be understood that the invention is adapted for use with other types of closures.

According to the invention disclosed on the drawings a pair of upward acting sectional type garage doors are mounted for vertical and horizontal movement in tracks supporting and guiding rollers extending from the sides of the doors. A metal mullion is removably mounted in vertical position between the doors and extends from the lintel of the doorway to the floor or sill. This mullion is preferably formed by extrusion of an aluminum alloy and is so shaped as to define tracks or guides on both sides thereof for the rollers projecting from the adjoining sides of the doors. The mullion carries resilient weatherstrips adapted to spring against the outer faces of the doors when the same are in closed position to seal any spaces between the doors and the mullion.

The bottom of the mullion is removably mounted in a fixed floor plate while the top of the mullion is readily latched into aligned position with the fixed tracks of the assembly.

A feature of the invention includes a safety lock, automatically operated by the insertion and

removal of the mullion so as to prevent the doors from being moved down when the mullion is removed.

It is then an object of this invention to provide a removable mullion for adjoining closures.

Another object of the invention is to provide an upward acting door construction including a plurality of adjoining doors having their adjacent sides guided and supported by a removable mullion.

A further object of the invention is to provide an upward acting door construction having a pair of adjoining doors guided along their adjacent edges in tracks adapted to be readily removed when the doors are in open position.

Another object of the invention is to provide an extruded aluminum alloy removable mullion for closures.

A further object of the invention is to provide a safety lock automatically operated by a removable mullion in an upward acting door construction for preventing closing of the doors when the mullion is removed.

A specific object of the invention is to provide a removable mullion for upward acting doors adapted to be quickly and easily latched into operative position for guiding and supporting the adjacent edges of a pair of doors as the doors are moved to a closed position.

Other and further objects of the invention will become apparent to those skilled in the art from the following detailed description of the annexed sheets of drawings which disclose a preferred embodiment of the invention.

35 On the drawings:

Figure 1 is a fragmentary elevational view of a doorway viewed from the inside thereof and having doors, according to this invention, mounted therein in closed position.

40 Figure 2 is a broken, fragmentary view similar to Figure 1 but illustrating the doors in opened position.

Figure 3 is an enlarged broken vertical cross sectional view, with parts in elevation, taken 45 along the line III—III of Figure 1.

Figure 4 is an enlarged fragmentary horizontal cross sectional view taken along the line IV—IV of Figure 1.

Figure 5 is an enlarged horizontal cross sectional view, with parts omitted, taken along the line V—V of Figure 1.

Figure 6 is an enlarged fragmentary elevational view taken along the line VI—VI of Figure 3.

55 Figure 7 is an enlarged fragmentary vertical

cross sectional view, with parts in elevation, taken along the line VII—VII of Figure 1.

Figure 8 is a fragmentary vertical cross sectional view, with parts in elevation, taken along the line VIII—VIII of Figure 7.

Figure 9 is an enlarged, broken, elevational view of a removable mullion according to this invention.

Figure 10 is a top plan view of the mullion shown in Figure 9.

As shown on the drawings:

In Figures 1 and 2, the reference numeral 10 designates a doorway defined by side door jambs 11 and 12, by a lintel 13 extending between the tops of the door jambs and by a floor 14 extending between the bottoms of the door jambs.

A roof or ceiling 13a extends inwardly from the doorway 10 at a level above the bottom of the lintel 13.

The doorway 10 is closed by a pair of doors A and B, mounted on rollers for horizontal movement below the ceiling or roof 13a and for vertical movement into the doorway. The doors A and B are of the horizontal sectional type with the door A composed of hinged-together sections a, a¹, a², a³, and a⁴ and the door B composed of hinged-together sections b, b¹, b², b³ and b⁴.

Vertical track 15 is secured to each side jamb 11 and 12 with the open faces of the tracks facing the doorway 10. Curved track sections 16 communicate with the tops of the track 15 and with horizontal tracks 17 extending inwardly from the doorway. The curved tracks 16 and the adjoining ends of the horizontal tracks 17 are supported from metal brackets 18 secured to the lintel 13. These brackets 18 also rotatably support pulleys 19.

A floor bracket 20 is fixedly mounted on the floor 14 in the center of the doorway 10. As best shown in Figure 5, the bracket 20 has a wide heel portion 20a, a base 20b extending forwardly therefrom and toe portions 20c defining curved sockets facing the heel portion.

A vertical mullion 21 (Figure 1) has the bottom end thereof mounted in the floor bracket 20. The mullion 21 as best shown in Figures 3 and 4 provides vertical tracks 22 and 23 on each side thereof.

As shown in Figures 3, 4, 9 and 10 the mullion 21 has a web portion 21a extending between the tracks 22 and 23 and a transverse outer wall or flange 21b. The bottom end of this transverse wall 21b abuts the heel 20a of the floor bracket 20 while the tracks 22 and 23 abut the curved sockets provided by the toes 20c of the bracket 20 as shown in Figure 5. Legs 21c and 21d extend from opposite sides of the web 21a between the back wall 21b and the tracks 22 and 23. These legs cooperate with the tracks to hold the door rollers therein as best shown in Figure 4.

As shown in Figures 1, 2 and 3, angle plates 24 are secured to the inner face of the lintel 13 above the floor bracket 20. These angle plates 24 have inwardly extending flanges 25 in abutting relation, each carrying a curved track section 26 and 27. The curved track 26 communicates with the track 22 of the mullion 21 while the curved track 27 communicates with the track 23 of the mullion 21.

Horizontal tracks 28 and 29 extend inwardly from the upper ends of the curved track sections 26 and 27 respectively.

As best shown in Figure 3, the inner ends of the horizontal tracks, such as the inner end of the track 28, are carried on a transverse support

30 suspended from the ceiling or roof 13a. This transverse support 30 extends across the entire width of the doorway so as to also carry the inner ends of the horizontal tracks 17. Counterbalancing spring actuated pulleys such as 31 are rotatably mounted in the support 30 in alignment with the pulleys 19 and with pulleys 32 and 33 rotatably carried by the flanges 25 of the angle plates 24. Separate cables such as 34 are adapted to be wound around the spring actuated pulleys such as 31, are trained over the pulleys 19, 32 and 33 aligned with the actuated pulleys and are secured at their other ends to the bottom door sections a and b.

As best shown in Figures 3, 7 and 8, the top of the mullion 21 fits under the lower ends of the curved tracks 26 and 27. A bracket 35 is bolted to the bottom of the lintel 13 to abut the top portion of the back wall 21b of the mullion as also shown in Figure 4.

The web 21a of the mullion 21 has a U-shaped plate 36 extending above the top thereof. Legs 37 of the plate fit over the sides of the web and are riveted thereto by rivets 38.

The plate 36 extends above the top of the mullion between the legs 21c and 21d and the tracks 22 and 23 thereof and is adapted to slide between the end portions of the adjoining curved track sections 26 and 27 which extend beneath the flanges 25 of the angle plates 24. These flanges 25 space the track ends to define a slot therebetween for receiving the portion of the plate 36 above the mullion.

A housing 40 for a spring-pressed latch bolt 41 is bolted to a plate 42 carried by the tracks 22 and 23 of the mullion 21 at the top ends of the tracks. The plate 42 can be secured to the tracks as by welding.

As best shown in Figures 3, 7 and 8, the bottoms of the flanges 25 of the angle plates 24 have a tooth defining portion 43 extending downwardly from their inner bottom edges and provided with inwardly sloping edge portions 43a. The tooth forms an abutment for the top of the latch bolt 41 to retain the mullion in seated position against the bracket 35 so that the mullion tracks will be in alignment with the curved track sections 26 and 27. The plate 36 holds the mullion against sidewise movement since it is snugly received between the curved track sections.

The latch bolt 41 has an actuating chain 44 projecting from the bottom of the housing 40 as shown in Figures 1, 3 and 9 so that the bolt can be retracted into the housing beneath the tooth 43 to permit an inward tilting of the mullion out of position for removing the same from the doorway.

The mullion is readily inserted into operative position in the doorway by first seating the bottom end thereof into the floor bracket 20 with the tracks 22 and 23 thereof abutting the toes of the floor bracket. The top of the mullion is then swung toward the doorway to position the plate 36 between the curved tracks. The sloping edge 43a of the tooth defining portions 43 will automatically retract the latch bolt 41 so that it will pass under the tooth 43 and will then snap into abutting relation against the other edge of the tooth. The latch bolt will thus hold the top end of the mullion against the bracket 35 and will prevent unintentional removal of the mullion.

The top end of the mullion slopes downwardly from the tracks 22 and 23 thereof as shown in

Figure 3 in order to facilitate a tilting of the mullion into operative position.

The flanges 25 of the angle plates 24 receive a bolt 50 therethrough as best shown in Figures 3, 7 and 8. The bolt 50 rotatably supports latch members 51 and 52 in alignment with the tracks 26 and 27 respectively. Each latch member 51 and 52 has a hook-like top portion 53 adapted to project into a slot 54 cut in each track 26 and 27. Each latch 51 and 52 also has a downwardly projecting tail portion 55 adapted to be abutted by the plate 42 of the mullion 21.

A spring 56 urges the top portions of both latch members 51 and 52 so that their hook-like ends 53 will extend through the slots 54. The action of the spring, however, is opposed by the plate 42 on the mullion 21 when the mullion is mounted into operating position as shown in Figures 3, 7 and 8. As therein shown the plate 42 abuts the tails 55 of the latches to retract the hook portions 53 from the slots. Whenever the mullion is removed from its operating position these tail portions 55 are released and the spring will move the latches to seat their hook-like ends into the track slots. When seated, these hook-like ends 53 will prevent a closing of the doors A and B, since they will obstruct the passage of the door rollers in the track sections 26 and 27.

This arrangement therefore provides an automatic safety lock preventing a closing of the door when the mullion is removed from the doorway. The safety locks are automatically unlatched when the mullion is mounted in operating position.

As shown in Figures 1 and 3 the door sections of the door A are hinged together by means of hinges 60 secured to the inner faces of adjacent door sections at the edges of the door sections. The sections of the door B are similarly hinged together by means of hinges 61.

Each hinge 60 and 61 can have the pivot pin 62 therefor carry a roller 63 mounted for movement in the tracks as shown in Figure 3.

The top door section a⁴ carries an additional set of rollers 64 on axles 65 mounted at the top of the door section along the edges thereof as shown in Figures 1 and 3. The top door section b⁴ of the door B carries similar rollers and axles.

When the mullion 21 is mounted in operative position as shown in Figures 1 and 3, the doors A and B can be operated along the vertical, curved, and horizontal tracks to move the door sections between a closed vertical position and an overhead open horizontal position. However, when the mullion is removed as shown in Figure 2, the doors A and B must be in open overhead position since the rollers 63 of the doors in closed position will prevent removal of the mullion. With the doors in their opened overhead position, the mullion can be readily removed as described above. The safety latches or locks then prevent the doors from being closed beyond the position shown in Figure 2 so that the doors can not fall out of their guiding and supporting tracks.

As best shown in Figures 4, 5 and 9 the transverse wall 21b of the mullion 21 has longitudinal grooves 70 formed along the inner face thereof near the outer ends of the wall. Resilient metal weather strips 71 are adapted to be snapped into these grooves 70 along the full length of the mullion. The weatherstrips 71 have free end portions 72 projecting inwardly from the wall 21b into abutting relation with the outer faces of the doors A and B as shown in Figure 4 for

sealing any spaces between the outsides of the doors and the mullion. The doors can readily slide relative to the weatherstrips since the strips are resilient and do not interfere with an opening and closing of the doors.

From the above descriptions it should be understood that the mullion constructions of this invention provide many desired advantages in door constructions and present required supports 10 and guides for adjoining upward acting doors. At the same time the mullions of this invention act as seals between adjoining doors or closures.

The mullions can be made of light-weight material such as aluminum alloy and can be produced at reasonable cost by an extruding process. Heat-treated extruded aluminum alloy mullions having tensile strengths of 30,000 pounds per square inch are very satisfactory.

I am aware that many changes may be made 20 and numerous details of construction may be varied through a wide range without departing from the principles of this invention, and I, therefore, do not purpose limiting the patent granted hereon otherwise than necessitated by the appended claims.

I claim as my invention:

1. In a construction having a doorway, a pair of adjacent track sections extending downwardly to the top of the doorway, a floor bracket anchored in the bottom of said doorway beneath the track sections, a removable mullion adapted

30 to be seated in said bracket, means projecting from the top of said mullion adapted to snugly fit between said track sections and latching means 35 for holding the mullion in operative position to extend between the track sections and the bracket.

2. In a door construction including a pair of 40 closures for closing a doorway, the improvement which comprises a pair of fixed tracks extending

to the top of the doorway in spaced adjoining relation, a socket floor plate in said doorway beneath the fixed tracks, a completely detachable mullion defining tracks adapted to cooperate with the fixed tracks for extending the latter to the bottom of the doorway, said mullion having a bottom portion complementary in shape with and 45 adapted to be seated in said floor plate, and an extension on the top of said mullion adapted to project between said fixed tracks for holding the mullion in alignment with the tracks whereby 50 said mullion can be seated in said floor plate and tilted normally to the doorway into and out of the doorway.

3. In a building having a doorway defined by a 55 lintel, side jambs and a floor, a bracket secured on said lintel having a flange extending into the building, a track carried by said flange and extending downwardly into the top of the doorway,

60 a removable mullion extending between the floor and the bottom end of said track, means extending from said mullion engageable with the flange carried track to prevent tilting motion of the mullion away from said track in a plane parallel with the door in closed position, said mullion having a track thereon cooperating with the first

65 mentioned track, a projection on the bottom of said flange defining an abutment normal to the faces of the flange, and a spring pressed latch bolt carried by the top of said mullion adapted to abut said abutment for preventing tilting of the mullion away from the flange carried track in a plane normal to the door in closed position whereby 70 said mullion is held in position in the doorway, said bolt also adapted to be retracted.

from said abutment to allow the mullion to be swung into the building for removal from the doorway.

4. In an upward acting door construction for a doorway including a pair of spaced adjacent closures for movement into and out of said doorway, the improvement which comprises a single mullion latching device, a removable mullion adapted to be seated on the bottom of the doorway and tilted normally to the doorway into and out of the doorway by manipulation of said single latching device, a pair of fixed tracks extending downwardly to the top of the doorway in spaced adjoining relation, an extension on the top of said mullion adapted to snugly fit between said tracks, and a keeper parallel with the doorway for said latching device.

5. In an upward acting door construction for a doorway including a pair of spaced adjacent closures for movement into and out of said doorway, the improvement which comprises a mullion latching device, a removable mullion adapted to be seated on the bottom of the doorway and adapted to be tilted normally to the doorway into and out of the doorway, a fixed track construction at the top of the doorway, means on the top of said mullion engageable with said track construction, and a keeper having a surface parallel with the doorway for retaining said latching device, said latching device being operable to clear the keeper for releasing the mullion from fixed position in the doorway.

6. In a vertically sliding door construction including a pair of laterally spaced, vertically acting doors adapted to be actuated to and from closing position relative to a door opening, a removable post adapted to be positioned in said door opening between said doors and having a pair of opposed tracks for guidingly receiving rollers on the doors, a pair of horizontal stationary tracks in fixed relation to the door opening adapted to be placed in communication with said post tracks and to receive the doors in withdrawn position thereof, means for laterally supporting said post tracks in operative position comprising laterally spaced retaining means in fixed relation to said stationary tracks, said post having means engageable with said retaining means, securing means on the post adjacent the top thereof, and a coacting element in fixed relation to the door opening and releasably engageable by said securing means to maintain said post in operative front-to-rear position, said post being swingable in a direction normal to the opening upon release of said last named means to remove the post in its entirety from the opening, and means at the bottom of the opening for restraining the post at its base.

7. In an upward-acting door construction for a doorway including a pair of spaced adjacent closures mounted for movement into and out of said doorway, the improvements which comprise a pair of spaced opposed fixed tracks for the doors extending to the top of the doorway, retaining means at the bottom of the doorway below said fixed tracks, a mullion adapted to be positioned in the doorway between the doors to extend from the fixed tracks to the retaining means and adapted to be removed in its entirety from the doorway, said mullion having means on the top thereof insertable between the spaced opposed tracks to hold the mullion against movement in planes parallel with the doorway, a keeper at the top of the doorway, means on said mullion releasably engageable with the keeper to

hold the top of the mullion against movement in planes normal to the doorway, and said retaining means at the bottom of the doorway releasably holding the bottom of the mullion against movement whereby said mullion can be swung normally to the doorway into and out of operative position.

8. In an upward-acting door construction for a doorway including a pair of spaced adjacent closures for movement into and out of said doorway, the improvement which comprises a mullion latching device, a removable mullion adapted to be seated on the bottom of the doorway and adapted to be tilted normally to the doorway into and out of the doorway, a fixed track construction at the top of the doorway, means on the top of said mullion engageable with said track construction, and a keeper for retaining said latching device, said latching device being operable to clear the keeper for releasing the mullion from fixed position in the doorway.

9. In an upward-acting door construction for a doorway including a pair of spaced adjacent closures mounted for movement into and out of said doorway, the improvements which comprise a removable post adapted to be disposed in the doorway between said closures for swinging removal in its entirety from the doorway, a fixed header mounted at the top of the doorway having a keeper associated therewith between said closures, means on said post adjacent the top thereof for releasable retaining engagement with said keeper to hold the post in operative position in the plane of removal thereof, a pair of laterally spaced tracks in fixed relation to said header, said post having means thereon engageable with said fixed tracks for laterally supporting the post, and positioning means disposed at the bottom of the doorway between the closures for retaining the bottom of the post to prevent displacement thereof at that point.

10. In a vertically slidable door structure including a pair of laterally spaced vertically slid-able doors, a removable post adapted to be dis-posed in the door openings between said doors for swinging removal in its entirety from the door opening in a direction normal to the plane of the opening, a fixed header at the top of the door opening having a keeper associated therewith, latch means on said post releasably engag-ing the keeper to hold the post in operative po-sition in the plane of removal thereof, a pair of laterally spaced tracks in fixed relation to said header, said post having means thereon engage-able with said fixed tracks for laterally support-ing the post, and positioning means disposed at the bottom of the door opening for retaining the base of said post to prevent displacement of the post at that point.

11. In a vertically sliding door structure in-cluding a pair of laterally spaced vertically slid-ing doors, a removable post adapted to be dis-posed in the door opening between the doors for swinging removal in a direction normal to the plane of the opening, a fixed header at the top of the door opening having a keeper associated therewith, means on said post for releasable re-taining engagement with said keeper to hold the top of the post in operative position in the plane of removal thereof, lateral positioning means secured to said header at a point above the top of the post in operative position thereof, means on said post engageable with said lateral po-sitioning means for laterally supporting the post, and positioning means disposed at the bottom of

the door opening between the doors for preventing displacement of the post at that point.

12. In a vertically slidable door construction including a pair of laterally spaced articulated vertically slidable doors, a removable post adapted to be disposed in the door opening between said doors for swinging removal in its entirety from the door opening in a direction normal to the plane thereof, said post having opposed vertically extending tracks on the sides thereof, a fixed header at the top of the door opening having a keeper, means on said post adjacent the top thereof for releasable retaining engagement with said keeper to hold the top of the post in operative position in the plane of its removal, a pair of laterally spaced tracks in fixed relation to said header adapted to register vertically and communicate with said post tracks, said post including means engageable with said fixed tracks for laterally registering and supporting the post, and further means at the bottom of said door opening for releasably retaining the base of the post to prevent movement of the post at that point.

13. In a vertically slidable door construction 25

including a pair of laterally spaced vertically acting doors adapted to be actuated to and from closing position relative to a doorway, a removable post adapted to be positioned in said doorway between said doors and having a pair of opposed tracks for guidingly receiving rollers on the door, a pair of horizontal tracks in fixed relation to said doorway having curved portions extending downwardly and opening to the top of 10 the doorway, said portions being adapted to communicate with said post tracks, means on said post engageable with said curved portions for laterally spacing and stabilizing the post, post restraining means in fixed relation to said doorway, means on the post adjacent the top thereof for releasable engagement with said fixed means to maintain the top of the post in operative front to rear position, and retaining means at the bottom of the doorway releasably holding the bottom of the post whereby said post is swingable in a front to rear direction normal to the plane of the doorway upon release of one of said retaining means to permit removal of the post in its 15 20 entirety from the doorway.

JOSEPH E. CASSE.
